UNITED STATES PATENT OFFICE.

BRITTON POULSON, OF FORT WAYNE, INDIANA, ASSIGNOR TO WILLIAM D. SCHIEFER, OF SAME PLACE, AND JOHN C. HUNT, OF CONCORD, MASSACHUSETTS.

DEVICE FOR DETACHING BUTTONS.

SPECIFICATION forming part of Letters Patent No. 379,604, dated March 20, 1888.

Application filed November 7, 1887. Serial No. 254,511. (No model.)

To all whom it may concern:

Be it known that I, BRITTON POULSON, of Fort Wayne, county of Allen, and State of Indiana, have invented a new and useful Improvement in Devices for Detaching Buttons, of which the following is a full, clear, and exact description, reference being had to the accompanying drawings, making part of this specification.

10 My invention relates to a device for removing buttons from shoes and other articles of wearing-apparel, &c., and constitutes an improvement upon a device for that purpose for which Letters Patent were granted to me July 15, 1887, No. 367,319.

It consists in a novel construction of case slotted from end to end on one side and provided with a knife or cutter adapting it to act with either end in advance; in a novel construction of the cutter whereby it is adapted to the form or construction of the case referred to, and in the arrangement of the opposing edges, inclines, and springs operating in connection with the cutter, as hereinafter described and claimed.

25 In the accompanying drawings, Figure 1 represents the cutter-face side of my improved device in elevation. Fig. 2 represents the device in longitudinal section in a plane at right angles to the plane of the knife or cutter, and Fig. 3 a transverse section through the same. Fig. 4 is a face view similar to Fig. 1, showing a modification in the form of the cutter.

30 A indicates the case, made, preferably, substantially U-shaped in cross-section, as shown in Fig. 3, with inwardly-turned flanges a a' on the ends of its arms, and with end plates, b b' , which give it the form of a hollow and approximately semi-cylindrical case. The end plates do not extend to the plane of the flanges a a' , a space, c , being left for the admission of the button, and the lips or flanges a a' extend only partly across the side of the case on which they are located, having a slot or space, c' , left between their adjacent edges for the passage of the shank of the button and the material securing it. The flanges are cut away near their ends, as indicated at a^2 , to give said ends a flaring form, which greatly facilitates

the admission and guidance of the button to 50 the slot c' and to the cutter located therein. The inner adjacent edges of the lips or flanges a a' , or the entire width of said flanges, if desired, are made pendent or are thicker along the central portion of their length, as shown 55 at d , and the ends of said thickened portion or ledges are beveled or inclined outward on the inner edges, as shown at d' , for a purpose which will appear. One of the lips, a' , has a V or U shaped recess, e , formed in its outer 60 face at or near the center of its length, and to the opposite lip, a , is secured a cutter, B, which is made beveled or tapering from its center toward both ends and beveled on its outer face to a cutting-edge on said tapering edge, as 65 shown at f f' . These tapering edges cross the slot c' obliquely, and the point f^2 of the cutter overlies the recess e in the edge of the flange a' , slightly removed from contact with the bottom of said recess. (See Figs. 1 and 3.) 70

To the end plates, b and b' , spring-plates g are secured, which extend inwardly toward each other, and, preferably, are made to diverge inwardly from the plane of the outer faces of the flanges a and a' . These springs 75 are made, preferably, to extend transversely across the casing and serve the double purpose of preventing the accidental escape of buttons from the case through the openings c and of holding the buttons steadily pressed up against 80 the ledges d in the process of detaching them.

The operation will be readily understood. The operator, taking the device in his hand, with either end in advance, and with the cutter-face to the shoe or other article from which 85 the buttons are to be removed, pushes the end toward a button or line of buttons, and the latter, entering the openings c , pass within the case, and, coming in contact with the inclined ends d' of the ledges d , are drawn inward until 90 the shanks are drawn inside the plane of the cutter B, leaving only the fastening material to be acted upon by said knife or cutter. The adjacent edge of the flange a' underlying said knife serves to hold said fastening material up 95 to the action of the cutter as the device is moved longitudinally over the button. A portion, b^2 , of one of the end plates is hinged to

a rigidly-fastened portion thereof or to the edge of the casing, and forms a small door, which may be fastened, when closed, by means of an elastic lip or flange on its outer edge, as shown, or in any suitable manner. This door enables the operator to remove the buttons from the case when required.

In Fig. 4 a circular cutter is shown pivoted to a flange, *a*, and overlying the slot *c'* and recess *e*, which is curved to conform to the shape of the cutter, as shown. The action of the cutter in this case will be readily understood, and the action of the device as a whole is the same as that above described.

Having now described my invention, what I claim as new, and desire to secure by Letters Patent, is—

1. The longitudinally-slotted case *A*, provided with the cutter crossing said slot and adapted to operate with either end of the case in advance, substantially as described.

2. The combination, with the longitudinally-slotted case or holder *A*, of the double-acting or two-edged cutter, substantially as and for the purpose described.

3. The hollow case *A*, having end openings, *c*, the longitudinal slot *c'*, pendent ledges *d*, and knife or cutter *B*, substantially as described.

4. The case or holder *A*, provided with the end openings, *c*, the longitudinal slot *c'*, and the tapering ledges *d*, of the spring-plates *g*, substantially as described.

5. The case or holder *A*, provided with the openings *c c*, the slot *c'*, ledges *d*, springs *g*, cutter *B*, and hinged door *b²*, all substantially as and for the purpose described.

In testimony whereof I have hereunto set my hand this 24th day of October, A. D. 1887.

BRITTON POULSON.
